[57] **CLAIM**

The ornamental design for a golf marker for recording longest drive or the like, as shown and described.

DESCRIPTION

FIG. 1 is a front elevational view of a golf marker for recording longest drive or the like showing my new design;

FIG. 2 is a side elevational view thereof;

FIG. 3 is a top plan view thereof;

FIG. 4 is a bottom plan view thereof; and

FIG. 5 is a rear elevational view thereof.

The post has been shown fragmented for ease of illustration.

The pencil shown in broken lines is for illustrative purposes only and forms no part of the instant design.
